Inventor.

Thomas C. Wentworth.

By. Alvin Sperry Jr.
Attorney.

UNITED STATES PATENT OFFICE.

THOMAS CLIFFORD WENTWORTH, OF CORNISH, MAINE.

COMBINATION REINFORCEMENT AND FASTENER.

Application filed May 13, 1921. Serial No. 469,161.

To all whom it may concern:

Be it known that I, THOMAS C. WENTWORTH, a citizen of the United States, residing at Cornish, county of York, State of Maine, have invented certain new and useful Improvements in Combination Reinforcements and Fasteners, of which the following is a specification.

This invention relates to a combination 10 reinforcement and cover fastener for shipping packages, and is particularly intended for use with the egg case of standard commercial type.

The object of my invention is to provide 15 a simple and inexpensive reinforcing fastener which while reliably securing the cover of the shipping case and effectively reinforcing the case, may be readily locked and unlocked as occasion requires.

20 This object, together with certain other features of advantage, is secured in the device of the present invention. The construction and operation of my reinforcing fastener is described and illustrated in the accompanying specification and drawings, and the characteristic features of novelty are particularly pointed out in the appended claims.

25 Throughout the specification and drawings, like reference characters are correspondingly employed, and in the drawings:

Fig. 1 is an end view of an egg case equipped with a reinforcing fastener in accordance with my invention.

30 Fig. 2 is a plan view thereof.

Fig. 3 is an enlarged detail section.

For the purposes of this application I shall discuss my invention in its adaptation to a shipping case for eggs, although it will be understood that such treatment is purely 40 illustrative and in no way limiting.

I have accordingly indicated at 1 an egg case of standard type and at 2 the cover therefor.

45 My combination reinforcement and fastening member consists of a clamping strip 3 of suitable material which is carried around the bottom and side walls of the case, being attached thereto as indicated at 4, and across the cover 2 of the case.

50 The ends of the band 3 are carried upwardly over and around a pair of bearing blocks 5 and 5' which are adapted to rest on the cover 2 in spaced relation to each other, and are secured to said blocks as indicated at 6.

The blocks 5 and 5' preferably have protective coverings 7 and 7' of sheet metal, tin or other suitable material fastened thereto, and their outer uncovered ends are preferably beveled, as indicated at 8, so that the ends of the flexible band 3 may be carried conveniently upwardly onto the top faces of the blocks, around the inner ends thereof, and along the bottom faces of the blocks.

60 The ends of the flexible band 3 are adapted to be detachably connected with each other by a locking member comprising, as here shown, a threaded bolt 9, the head 10 of which is lodged between the cover 7 for the block 5 and the inner end of said block itself. The opposite end of the bolt 9 is threaded as indicated at 10, and passes through the cover 7' of the opposite block 5' and into a bore 5² tapped into said block. 65 Preferably a bearing piece 11 is secured between the inner face of said cover 7' and the inner end of block 5' and is tapped and threaded as shown to receive said bolt.

70 Fast on the bolt 9 is a wing nut 12 by means of which the blocks may be drawn towards each other to tighten the band 3. If necessary, the upper face of the cover 2 between the blocks 5 and 5' may be recessed as indicated at 13 to permit the nut 12 to 75 turn freely on the bolt 9.

80 In use, the cover 2 is fastened by entering the threaded end 10 of the bolt 9 into the bore 5² of block 5' and turning the nut 12 in the proper direction to draw the blocks toward each other, thereby tightening the 85 flexible band 3.

85 The cover is released by backing off the nut 12, thereby permitting the blocks to separate.

90 Inasmuch as the blocks are fastened to the band, and the head of the bolt 9 is retained between the cover 7 and the block 5, there is no liability of either the blocks or the bolt becoming lost when the clamp is released.

95 By this construction, the usual hinges and lock for the cover may be dispensed with.

100 It will also be noted that the head and threaded end of the bolt 9 are set through the ends of the strip 3 itself (see Fig. 3) so that the strip is thereby additionally fastened to the blocks when the fastener is tightened.

105 Various modifications in the form and construction of my device may obviously be resorted to all without departing from the 110

spirit of my invention if within the limits of the appended claims.

What I therefore desire to secure by Letters Patent is:

5. 1. A band fastener consisting of a pair of oppositely disposed spaced bearing blocks to which ends of the band are fastened, covering for said blocks, a bolt having its head lodged between the covering of one 10 of said blocks and the block itself and having its opposite end entered through the covering of and into the opposite block and a nut on said bolt disposed in the space between said blocks for drawing said blocks 15 towards each other to tighten the band.
2. A combination reenforcement and fastener for the cover of a shipping case, comprising a clamping strip passed around

the walls of the shipping case, a pair of bearing blocks adapted normally to rest on 20 the cover in spaced relation to each other, and to which the ends of the strip are fastened, coverings for said blocks, a bolt having its head lodged between the covering for one of said blocks and the block itself and 25 having its opposite end entered through the covering of and into the opposite block, and a nut on said bolt for drawing said blocks towards each other to tighten the clamping strip.

In testimony whereof I affix my signature in presence of two witnesses.

THOMAS CLIFFORD WENTWORTH.

Witnesses:

WILLIAM B. RANDALL,
HOWARD WENTWORTH.
